UNITED STATES PATENT OFFICE.

PHILLIP H. LETTRÉ, OF ATTLEBORO FALLS, MASSACHUSETTS, ASSIGNOR
TO T. I. SMITH CO., OF NORTH ATTLEBORO, MASSACHUSETTS.

BRACELET.

No. 809,619.

Specification of Letters Patent.

Patented Jan. 9, 1906.

Application filed June 3, 1905. Serial No. 263,572.

To all whom it may concern:

Be it known that I, PHILLIP H. LETTRÉ, a citizen of the United States, residing at Attleboro Falls, in the county of Bristol and State of Massachusetts, have invented a new and useful Improvement in Bracelets, of which the following is a specification.

This invention has reference to an improvement in bracelets, and more particularly to an improvement in the construction of the hinge and catch of a bracelet.

The object of my invention is to improve the construction of bracelets whereby a bracelet is provided with a strong and durable spring-actuated concealed hinge and a practically concealed catch, the construction of which is simplified and strengthened.

My invention consists in the peculiar and novel construction of a bracelet embodying a spring-actuated concealed hinge and a one-piece catch, whereby the bracelet is opened against the tension of the spring, closed automatically, and held in the closed position by the catch, with details of construction, as will be more fully set forth hereinafter.

Figure 1 is a side view of a bracelet embodying my invention, showing the bracelet in the closed position in full lines and in the open position in broken lines. Fig. 2 is an enlarged detail sectional view looking at the back of the hinge, showing the shell of the bracelet broken away to clearly show the construction of the hinge. Fig. 3 is an enlarged detail sectional view looking at the side of the hinge, showing the shell of the bracelet broken away and the hinge in the closed position. Fig. 4 is an enlarged detail sectional view taken on a central line drawn from the outside to the inside of the bracelet, showing the hinge in the open position. Fig. 5 is an enlarged detail sectional view showing the catch holding the ends of the bracelet in the closed position, and Fig. 6 is an enlarged detail sectional view showing the end of the bracelet released from the catch.

In the drawings, *a* indicates one semicircular half, *b* the other semicircular half, *c* the spring-actuated concealed hinge, and *d* the catch, of my improved bracelet. The semicircular halves *a* and *b* are in the form of a tube or hollow shell. The half *a* has the end *a'* for the hinge *c* and the end *a''*, in which is the slot *a''*, for the catch *d*. The

half *b* has the end *b'* for the hinge and the end *b''*, having the inwardly-turned lip *b''* for the catch *d*.

The hinge *c* consists of a member *c'*, having the body portion *c''*, shaped to fit in the end *b'* of the bracelet and the forked end *c''*; a member *c''*, having the body portion *c''*, shaped to fit in the end *a'* of the bracelet; the tongue *c''*, adapted to enter the forked end *c''*, in which it is pivotally secured by the pin *c''*, forming the pintle of the hinge, and the slot *c''*, extending into the end of the body portion *c''*; a square tube *c''*, in which is a coiled spring *c''*, one end of which is secured to the member *c'* in the slot *c''* by the pin *c''*, and the other end to the bar *c''*, extending across the outer end of the tube *c''*. The members *c'*, *c''*, and *c''* of the hinge are all curved to conform to the contour of the bracelet, as shown in Fig. 3. The hinge is secured in the bracelet by soldering the body portion *c''* of the member *c'* in the end *b'* of the bracelet and soldering the cross-bar *c''* or the adjacent end of the tube *c''* in the end *a'* of the bracelet, with the halves *a* and *b* of the bracelet in the closed position.

The catch *d* is stamped from sheet metal, substantially U-shaped, as shown in Fig. 6. The arm *d'* has the rounded end *d''*, and the arm *d''* has the rounded end *d''*, the notch *d''*, and the outwardly-extending push-teat *d''*. The catch *d* is placed in the end *a'* of the bracelet in a position for the push-teat *d''* to extend through the slot *a''* in the end *a'* and secured by soldering the arm *d'* to the inside of the bracelet.

In the operation of my improved bracelet the bracelet is opened by pushing on the push-teat *d''* and forcing the two halves of the bracelet apart against the tension of the coiled spring, as shown in broken lines in Fig. 1 and full lines in Fig. 4. The outer edges of the ends *a'* and *b'* act as a fulcrum to draw the member *c'* and the tube *c''* apart against the tension of the spring *c''*, as shown in Fig. 4. The bracelet closes automatically by the tension of the spring *c''*, and the ends *a''* and *b''* lock automatically by the lip *b''* on the end *b''* entering the notch *d''* in the catch *d*, as shown in Fig. 5.

By this construction I provide a bracelet with a strong spring-actuated concealed hinge and a one-piece automatic catch, whereby the

bracelet is easily opened and automatically closed and locked in the closed position when released.

It is evident that the shell of the bracelet 5 could be circular or square in cross-section and that the bracelet could have any design or configuration desired without materially affecting the spirit of my invention.

Having thus described my invention, I claim 10 as new and desire to secure by Letters Patent—

1. A two-part tubular bracelet having a spring-actuated concealed hinge consisting of a member having a body portion with a forked end, a member having a body portion with a 15 tongue adapted to enter the forked end of the adjacent member in which it is pivotally secured by a pin, a tube, a coiled spring in the tube one end of which is secured to the member having the tongue and the other end secured to a bar crossing the outer end of the tube, a catch stamped substantially U-shaped from sheet metal the arms of which are rounded on the ends, one arm having a notch and a push-teat adapted to extend through a slot in 20 the bracelet, and means for securing the hinge and catch, whereby the bracelet is opened against the tension of the coiled spring without forming a gap or opening in the hinge-joint of the bracelet, and closed automatically 25 by the tension of the coiled spring, as described.

2. In a bracelet, the combination with the half *a* having the end *a'* and the half *b* having the end *b'* of a bracelet, of a spring-actuated 30 concealed hinge *c* consisting of a member *c'* having the body portion *c'* with the forked end *c'*, a member *c''* having the body portion *c''*, the tongue *c''* adapted to enter the forked end *c'* in which it is pivotally secured by the pin

*c*⁷ forming the pintle of the hinge, and the slot *c*⁸ extending into the body portion *c'*, a tube *c*⁹, a coiled spring *c*¹⁰ in the tube, one end of the spring being secured to the member *c'* in the slot *c*⁸ by the pin *c*¹¹ and the other end to the bar *c*¹² extending across the outer 45 end of the tube *c*⁹, and means for securing the hinge in the bracelet, as described.

3. In a bracelet, the combination with the half *a* having the end *a'*, the end *a''* in which is the slot *a*³, and the half *b* having the end *b'* and the end *b''* in which is the inwardly-extending lip *b*³, of a spring-actuated concealed hinge *c* consisting of a member *c'* having the body portion *c'* with the forked end *c'*, a member *c''* having the body portion *c''*, and the tongue *c''* adapted to enter the forked end *c'* in which it is pivotally secured by the pin *c*⁷ forming the pintle of the hinge, and the slot *c*⁸ extending into the body portion *c'*, a tube *c*⁹, a coiled spring *c*¹⁰ in the tube, one end of the spring *c*¹⁰ being secured to the member *c'* in the slot *c*⁸ by the pin *c*¹¹ and the other end to the bar *c*¹² extending across the outer end of the tube *c*⁹, and a U-shaped catch *d* having the arm *d'* with the rounded end *d*² and the arm *d*³ with the rounded end *d*⁴, the notch *d*⁵ and the outwardly-extending push-teat *d*⁶, means for securing the hinge *c* in the ends *a'* and *b'* of the bracelet, and means for securing the catch *d* in the end *a''* of the bracelet, as described. 70

In testimony whereof I have signed my name to this specification in the presence of two subscribing witnesses.

PHILLIP H. LETTRÉ.
